UNITED STATES PATENT OFFICE.

FREDERICK MANKEY, OF WILLIAMSPORT, PENNSYLVANIA.

DESIGN FOR THE SURFACE ORNAMENTATION OF WALLS, &c.

SPECIFICATION forming part of Design No. 16,365, dated November 3, 1885.

Application filed July 18, 1885. Serial No. 171,994. Term of patent 7 years.

To all whom it may concern:

Be it known that I, FREDERICK MANKEY, of Williamsport, Lycoming county, Pennsylvania, have invented and produced a new and original Design for Surface Ornamentation of Walls, &c., of which the following is a specification, reference being had to the accompanying photograph, forming part hereof.

My design consists in a figure of the shape of a Maltese cross formed upon the surface by eight trilateral pyramids, A B C D E F G H. The pyramids A B form one arm of the cross, C D another, E F another, and G H another. Said pyramids are separated by oppositely-inclined diagonal channels I J, transverse channels K, and longitudinal channels L. The figure thus formed is repeated in rows, and the several figures are separated by transverse channels M and longitudinal channels N.

In applying this design I may not employ the entire Maltese cross formed as described, but may restrict the design to pairs of trilateral pyramids separated by diagonal channels, as B C separated by the channel I, and D E separated by the oppositely-inclined channel J, the elevations B C and D E alternating in the row, and being also separated by the transverse channels K and M.

I claim—

1. The design for surface ornamentation of walls, &c., substantially as herein shown and described, consisting in a Maltese cross formed by eight trilateral pyramidal elevations, each arm of said cross being formed by two of said elevations, as A B, C D, the said elevations being separated by diagonal channels I J, transverse channels K, and longitudinal channels L, and the said figure being repeated in rows transversely and longitudinally, and the said rows being separated by transverse channels M and longitudinal channels N.
2. The design for surface ornamentation of walls, &c., substantially as herein shown and described, consisting in two trilateral pyramidal elevations, B C, separated by a diagonal channel, I, and two trilateral pyramidal elevations, D E, separated by an oppositely-inclined diagonal channel, J, the said elevations B C and D E alternating in a row and separated by transverse channels K M.

FREDERICK MANKEY.
